UNITED STATES PATENT OFFICE.

WILLIAM CUTLER, OF BIRMINGHAM, ENGLAND.

FURNACE FOR BENDING AND SHAPING SHEET-GLASS, &c.

SPECIFICATION forming part of Letters Patent No. 787,437, dated April 18, 1905.

Application filed March 30, 1904. Serial No. 200,738.

To all whom it may concern:

Be it known that I, WILLIAM CUTLER, manufacturer, a subject of the King of Great Britain, and a resident of 71 Gough road, Edgbaston, Birmingham, in the county of Warwick, England, have invented certain new and useful Improvements in and Relating to Furnaces for Bending and Shaping Sheet-Glass and the Like, (for which I have applied for a patent in Great Britain, Patent No. 28,307, dated the 24th day of December, 1903,) of which the following is a specification.

This invention relates to furnaces for bending and shaping sheet-glass and the like in a mold by the action of the atmospheric pressure on the one side of the glass when heated while the air is being exhausted, so as to remove the pressure from the other side, as set forth in United States Patent No. 544,248, dated the 7th of August, 1895, the object of these improvements being to facilitate the rapid placing and fixing of the sheet-glass in the molds and the removal of the articles therefrom after being shaped, as also the rapid connection and disconnection of the vacuum-pipe to and from the mold without materially affecting the temperature of the heating-chamber.

In order that this invention may be clearly understood and more easily carried into practice, I have appended hereunto two sheets of drawings, upon which I have illustrated the nature of my said invention.

Figure 1 is a longitudinal section through the furnace with the mold in position ready for the insertion of the sheet-glass or the removal of the finished article. Fig. 2 is a side elevation of the furnace shown by Fig. 1. Fig. 3 is a cross-section on the line A B through the furnace illustrated by Fig. 1, but showing the mold in position as when under exhaust. Fig. 4 is an enlarged view of the clips for raising the clamp, as shown by Fig. 1. Fig. 5 is a plan of the mold-clamp when detached. Fig. 6 is a section of the connection to the mold exhaust-pipe.

In carrying this invention into effect the furnace consists of a grate 2 and two chambers 3 and 4, the heating one, 3, of which is placed in a position adjacent to the grate 2, from which it is divided by a suitable bridge

5. Upon the reverse side of the heating-chamber 3 to that of the grate 2 the change-chamber 4 is provided for the insertion of the glass and the removal of the articles from the mold 7, while the flue 8 to the stack 9 is 55 preferably placed over or below and in close proximity to the heating-chamber 3 and is provided with a suitable damper for the regulation of the draft.

The mold 7 is placed upon a truck 27, which 60 is mounted to travel on a tramway running between the heating and change chambers, by which means the sheet of glass can be inserted in the mold and the article removed 65 through the outer door 10 without materially affecting the temperature of the heating-chamber 3.

For retaining the sheet-glass in the mold 7 during the operation of the vacuum process a heavy metal frame or clamp 11 requires to be 70 lowered and deposited upon the mold 7, and such lowering action must be effected with a perfectly true vertical movement, so as to always find its correct seat upon the mold, to effect which a lever 12 is pivoted upon a support which is fixed to the furnace, such lever being provided with a grooved segment 13 at the end, with the pivot 14 at its center and which is immediately over the mold 7, while an operating-handle 15 is suspended from the 80 other end of the lever. One end, 16, of a vertically-hanging chain 17 is fixed to the extreme top 16 of the segment and rests in the segment-groove, by which means the chain 17 has a true vertical movement, and thereby 85 raises and lowers the mold-clamp 11 in the same manner. Toggle or other suitable clips or clutches 18 are provided upon a suitable frame-terminal 19 to the chain 17, which engages with the projections 28 of the clamp 11 90 when raising same and which can be disengaged therefrom when so required to allow of the mold and clamp passing into the heating-chamber. In place of the segment the frame 11 may be raised by other means, such 95 as a chain passing over grooved pulleys.

The vacuum-pipe 20, which projects from the mold 7 in a horizontal direction, is provided with a flanged end 21 and is sufficiently large to allow the end of the connecting-pipe 100

22 to socket thereon, such connecting-pipe being provided at one end with a flange 23, which butts against the flange 21 upon the mold-pipe, and thereby forms a practically 5 air-tight connection, while the other end of the pipe 22 is adapted to be connected to the pump or other means for exhausting the air by a flexible pipe, thus enabling the pipe connection to be rapidly made through the aperture 25, which is provided in the side of the heating-chamber, a small sliding door 26 being provided above to enable the workman to readily make the connection and watch the action of the glass in the mold.

15 Having now described my invention, what I claim as new, and desire to secure by Letters Patent, is—

The improvements in and relating to fur-

naces for vacuum bending and shaping sheet-glass and the like, characterized by a pair of 20 heating and change chambers having a tram-way connection between the two with truck for conveying the mold from one to the other, in combination with a mold, a clamp, an exhaust-pipe, a vertically-moving clutch operated from the exterior for raising and lowering the clamp, an aperture or door in the side of the furnace and means for coupling up the exhaust-pipe to the mold substantially for the purpose set forth.

25 In witness whereof I have hereunto set my hand in the presence of two witnesses.

30 WILLIAM CUTLER.
